AUTOMOBILE HOOD CLAMP

Original Filed Oct. 28, 1924

INVENTOR.
RAYMOND G. MOORE.
BY *Frank W. Matteson*.
ATTORNEY.

UNITED STATES PATENT OFFICE

RAYMOND G. MOORE, OF BRIDGEPORT, CONNECTICUT, ASSIGNOR TO THE BASSICK COMPANY, OF BRIDGEPORT, CONNECTICUT, A CORPORATION OF CONNECTICUT

AUTOMOBILE HOOD CLAMP

Original application filed October 28, 1924, Serial No. 746,294. Divided and this application filed October 25, 1926. Serial No. 143,946.

The present invention relates to improvements in automobile hood clamps, the present application being a divisional application of my former application which matured 5 into Patent No. 1,637,530, Aug. 2, 1927. The invention relates particularly to hood clamps adapted for heavy usage, as upon trucks or buses, a principal object being to provide a clamp of this character, in which 10 the barrel is formed of sheet metal pressed to shape.

In accordance with the present embodiment of the invention, it is proposed to provide a sheet metal barrel having integral attachment portions for securing the same in relation to a part of the hood structure, and whereby a simple and economical construction of relatively great strength is provided.

Other objects consist in providing a device 20 of this character, which may be conveniently and economically manufactured by efficient fabricating processes, and in which the barrel is produced by an improved method which enables it to be constructed from sheet 25 metal and assembled with the hood and the other parts of the clamp, so that the whole structure is of relatively great strength and durability.

With the above and other objects in view, 30 an embodiment of the invention is shown in the accompanying drawings, and this embodiment will be hereinafter more fully described with reference thereto, and the invention will be finally pointed out in the 35 claims.

In the drawings:—

Fig. 1 is a side elevation of a hood clamp, according to the present embodiment of the 40 invention, and showing in dotted lines the inoperative or unclamped position thereof;

Fig. 2 is a front elevation of the same, partly in section;

Fig. 3 is a plan view of the barrel forming blank;

Fig. 4 is a side elevation of the blank, after the first forming operation, the same being bent to U-shape in cross-section;

Fig. 5 is a top view of the same;

Fig. 6 is a side elevation of the blank, af-

ter the final forming operation, the same being bent to tubular form; and

Fig. 7 is a top view of the same.

Similar reference characters indicate corresponding parts throughout the several figures of the drawings.

Referring to the drawings, the invention is particularly adapted for use with hoods in which each side of the same comprises an upper hinged flap 10 and a side hinged flap 11, the clamp proper being secured upon the side flap, while the keeper is secured upon the upper flap.

According to the present embodiment of the invention, the cylindrical barrel 12 is formed from flat sheet metal, blanked to shape to provide projecting lugs 13 and 14 along the top edge and lugs 15 and 16 along the bottom edge. At each end there are provided projecting flap portions 17 and 18 apertured at their corners, as at 19, for engagement of attaching screws, the upper and lower edges of the flaps being spaced from the upper and lower edges of the blank, and cut into the same as at 20.

The blank is first pressed to U-shape in cross-section, as indicated in Figs. 4 and 5, and the same is then pressed into barrel form, the upper and lower end portions being brought together into cylindrical form, while the flap portions 17 and 18 are turned inwardly and bent outwardly in opposite directions in the same plane, as indicated in Figs. 6 and 7.

The plunger and end cap assembly is now 85 inserted and secured. The plunger 21, which is provided at its upper end with an eyelet 22, has upper and lower apertured and flanged end caps 23 and 24 engaged thereon, the spring 25 being engaged about the 90 plunger between wear-washers 26 bearing upon the upper cap 23 and a washer 27 secured upon the plunger by pinching the same, as at 28, wear-washers 29 being also provided at the inner side of the lower cap 24. 95 The closure caps are slotted, as at 30, and are engaged over the ends of the barrel, the lugs at the ends of the barrel being projected through the slots and bent over to secure the caps, as clearly indicated in Fig. 2.

A forked toggle lever 31 is pivoted to the eyelet end of the plunger, and includes a forked nose portion 32 engaged at each side of the eyelet and pivoted by means of a pivot pin 33, and a ring-shaped handle portion 34.

The clamp is secured to the side hood flap by means of screws 35, and is adapted to co-operate with a keeper 36 secured to the top hood flap and provided with a projecting hooked portion 37, forked to engage at each side of the plunger beneath the forked nose ends of the toggle lever. The full lines, Fig. 1, and Fig. 2, indicate the clamped position in which the plunger is drawn upwardly with respect to the barrel and the toggle lever is engaged with the keeper with the nose ends forwardly of the vertical line through the pivot and the handle abutting the upper surface of the keeper. The clamp is disengaged by swinging the toggle lever outwardly to release it from the keeper, and permitting the side hood flap to be swung outwardly to the dotted line position, Fig. 1.

I have illustrated and described a preferred and satisfactory embodiment of the invention, but it will be obvious that changes may be made therein, within the spirit and scope thereof, as defined in the appended claims.

Having thus described my invention, what I claim and desire to secure by Letters Patent is:—

1. In a clamp, a tubular barrel formed of sheet metal bent transversely into tube form, integral extensions extending transversely from each side of said barrel adapted for attachment to a part of the clamped structure, integral projecting lugs at the upper and lower ends of said barrel, and end closure caps engaged over the ends of the barrel to secure the tubular relation thereof and having slots engaged by said lugs, said lugs being bent over upon said caps to secure them.
2. In a clamp, a tubular barrel formed of sheet metal bent transversely into tube form, integral extensions extending transversely from each side of said barrel adapted for attachment to a part of the clamped structure, centrally apertured end closure caps engaged over the ends of said barrel to secure the tubular relation thereof, a spring actuated plunger in said barrel extending through said apertures of said caps, and keeper engaging means mounted upon one end of said plunger.
3. In a clamp, a tubular barrel formed of flat sheet metal bent transversely into form and having slits extending transversely from each end at points spaced from the upper and lower edges, the upper and lower end portions of the barrel above and below said slits being brought together at their vertical edges to form circumferentially closed tube portions having seams at the inner side of said barrel, and the portions between said slits being bent outwardly and extending trans-

versely from each side of the barrel to form integral attachment portions, the lines of bending of said attachment portions being spaced from each other providing an opening at the seam side of said barrel, and the inner surface of said portions, being inwardly spaced with respect to said tubular end portions, whereby they are adapted to engage and be attached to the surface of a part of the clamped structure to space said tubular end portions outwardly therefrom, said opening being concealed and closed by the clamped structure in the attached relation of the clamp, and said seams of the tubular end portions being disposed toward the clamped structure.

Signed at Bridgeport, county of Fairfield, and State of Connecticut, this 5th day of October, 1926.

RAYMOND G. MOORE.
